CLAIM

(57) The ornamental design for a wearable device, as shown and described.

DESCRIPTION

FIG. 1 is a front view of a wearable device showing our new design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The oblique shade lines in the Figures show a transparent, reflective, or shiny surface, and not surface ornamentation. The dashed broken lines in the Figures show portions of the wearable device that form no part of the claimed design. The dot dashed broken lines in the Figures show boundaries that form no part of the claimed design.
